UNITED STATES PATENT OFFICE.

EBENEZER H. ROGERS, JR., OF NEW YORK, N. Y., ASSIGNOR TO THE ROGERS AUTOMATIC TIME STAMP COMPANY.

TIME-STAMP.

SPECIFICATION forming part of Letters Patent No. 412,900, dated October 15, 1889.

Application filed July 16, 1887. Serial No. 244,446. (No model.)

To all whom it may concern:

Be it known that I, EBENEZER H. ROGERS, Jr., of New York, in the county and State of New York, have invented certain new and useful Improvements in Time-Stamp, of which the following is a specification.

This invention relates to time-stamps for imprinting upon a document or paper the date, time of day, and other suitable information which it is desired said document or paper should bear.

I will describe in detail a time-stamp embodying my invention, and then point out the novel features in the claims.

15 In the accompanying drawings, Figure 1 represents a front elevation with the clock-face and frame carrying the impression-handle removed. Fig. 2 is a rear elevation. Fig. 3 is a section taken in line $x-x$ of Fig. 1 and 20 looking in the direction as indicated by the arrow. Fig. 4 is an end elevation of that portion of the device carrying the clock-movement, looking in the direction indicated by the arrow. Fig. 5 represents a detached view 25 of the sector having P. M. and A. M. type thereon and the actuating mechanism connected therewith. Fig. 6 represents a detached view of the month-sector and a part of its actuating mechanism connected therewith.

30 Fig. 7 is an end view of the trip-toe, illustrating the manner in which it engages with the toe of the spring-ring connected with the day-wheel, which will be clearly described hereinafter. Fig. 8 is a detached view of the day-wheel, upon which is secured the spring-ring. Fig. 9 is a detached elevational view of the 35 spring-ring. Fig. 9^a is a detail sectional view illustrating the relative position of the day-wheel and month-sector and the devices for operating the latter from the former. Fig. 10 is a 40 detached view of the year-sector; and Fig. 11 is a view, partly in section and partly in elevation, of the year-sector and frame of the machine. Fig. 12 is an enlarged detail view 45 of a polygonal prism, the dotted lines in this figure representing the thickness of the bed. Fig. 13 represents a detached view of one of the cams mounted on the hour-hand shaft of the clock-movement. Fig. 14 represents a 50 vertical section of the main-shaft sleeves and wheels mounted thereon. Fig. 15 is a plan

detail, on an enlarged scale, of the upper part of the stamp. Fig. 16 is a detail sectional view taken on line $y-y$ of Fig. 4, the better to illustrate the relation of the gears of the hour-hand shaft to the shaft carrying certain cams, to be referred to hereinafter.

Similar letters refer to similar parts throughout the drawings, in which—

A represents the platform, upon which is a 60 frame B. On the top of this frame is a bed C, provided with bearings a , adapted to receive the bearings of a shaft carrying the polygonal prism D, (see Fig. 12,) the edges of which are provided with grooves b , adapted to 65 receive the toe of the spring c , secured to the under side of the bed aforesaid. This polygonal prism D is to be operated by turning a wheel D (shown only in Fig. 15) with the hand, and is held in place by the aforesaid spring 70 c . At its ends the bed C is provided with rollers d , adapted to carry an inking-ribbon. By this means the inking-ribbon may be adjusted and carried over the bed aforesaid in the usual manner.

E, Figs. 1 and 3, represents the main driving-shaft having the hour type-wheel F rigidly mounted thereon. Upon this shaft E is sleeved the minute type-wheel G, and upon the sleeve of this wheel G is sleeved the A. M. 80 and P. M. type-sector H. There is also sleeved on the shaft E, on the opposite side of the hour type-wheel F, the day type-wheel I. Upon the sleeve of the said wheel I is sleeved the month type-sector K.

85 All the type wheels and sectors mentioned above, together with the year type-sector L, (see Fig. 10,) are arranged and are supported from the shaft E. They are also operated independently of each other between the vertical sides of the frame B. Upon that portion of the sleeve of the day-wheel I projecting beyond the frame B is rigidly mounted the ratchet-wheel M, provided with thirty-one teeth which engage with the stop-pawl N, 95 held against said wheel by means of the spring e , bearing upon the pin f , made fast to the body of the said pawl N. There is rigidly fixed to the shaft E, in front of the ratchet-wheel M, the star-wheel O, adapted to engage 100 with the stop-pawl P, which is held against the said star-wheel O by means of the spring

g, bearing upon the pin h, made fast to said pawl P. There is also pivotally mounted upon the front side of the frame B the deer-foot pawl R, the toe i of this pawl being 5 adapted to engage with the teeth of the aforesaid ratchet-wheel M. A portion of this pawl has a curved extension R', which, should the wheel M, from its momentum or other cause, be turned violently farther than the proper distance, is made to rise by the blows of the teeth against the toe i, and thus catch against the teeth of said wheel and allow the pawl N to take its proper place. There is connected 10 with the arm carrying the aforesaid deer-foot pawl R one end of the connecting-rod S, the other end of this rod being connected with the pawl T. The latter is mounted upon one end of the spring k. The other end of said spring k is secured to a fulcrumed arm k', and the 15 end of the latter bears upon the conical portion of an adjusting-screw k''. The toe of the pawl T engages with the cam T', (see Fig. 13,) mounted upon a short shaft V³, impelled by the rotation of the hour-hand shaft of the 20 clock-movement. There is also fulcrumed to the front side of the frame B the arm T², carrying on its upper end the deer-foot pawl T³, adapted to engage with the ratchet-wheel T⁴, mounted on the shaft T⁵, carrying the pinion T⁶, the teeth of which mesh with those of the 25 pinion T⁷, (see Fig. 5,) which is mounted on a stud secured to the frame B. This pinion T⁷ carries the spider-wheel T⁸, the arms T⁹ of which engage with the toe or arm T¹⁰ of the 30 A. M. and P. M. sector H, which is also provided with the seconds-arm T¹¹, which presses against the retracting-spring T¹² whenever the arm or toe T¹⁰ is raised by either of the arms of the said spider-wheel, so that when 35 the toe shall have dropped from the arm of the spider the spring T¹² will carry the arm back to its normal position, thus carrying the sector H likewise. The arm T² is also connected with one end of the connecting-rod T¹³, the other end of which is connected with the pawl V, the toe of which is adapted to 40 engage with the cam V', rigidly fixed to the short shaft of the clock-movement. This pawl V is mounted and secured to the frame 45 of the clock-movement similar to that of the pawl T, hereinbefore mentioned. There is also mounted upon the front of the frame B the stop-pawl V², adapted to engage with the ratchet-wheel T⁴. This pawl V² is mounted 50 the same as the pawl P, mentioned above.

Referring to Fig. 2, E is the main driving-shaft of the type-wheels. Upon this shaft E is mounted the ratchet-wheel D', adapted to engage with the deer-foot pawl D², secured to 55 the arm D³, fulcrumed to the rear side of the frame B. Said arm D³ is connected with one end of the connecting-rod D⁴. The other end of the latter is connected with the pawl D⁵, which is mounted on one end of the spring-blade D⁶. The other end of the latter is secured to the arm D⁷, fulcrumed to the frame 60 of the clock-movement. The end of the said

arm D⁷ bears upon the conical portion of an adjusting-screw D⁸, adapted to be operated to increase or decrease the tension of the spring-blade D⁶. The toe of said pawl D⁵ engages with the cam D⁹, mounted on the hour-hand shaft of the clock-movement. 70

On that portion of the minute type-wheel sleeve projecting beyond the rear portion of the frame B is rigidly fixed the ratchet-wheel D¹⁰, provided with sixty teeth adapted to engage with the deer-foot pawl D¹¹, secured to the fulcrumed arm D¹². With the body of the latter is connected one end of the connecting-rod D¹³, the other end of which is connected with the arm D¹⁴, the lower end of which is secured to one end of the spring-blade D¹⁵. The other end of the latter is secured to the fulcrumed arm D¹⁶, one end of which bears upon the conical portion of an adjusting-screw D¹⁷. There is connected with the arm D¹⁴ the pawl or toe D¹⁸, adapted to engage with the ratchet-wheel E', mounted on the hour-hand shaft of the clock-movement. 80 Said ratchet-wheel E' is provided with sixty teeth. Behind the milled head E² is fixed a pinion adapted to engage with the gear-wheel E³. Said milled head is operated when setting the machine ready for action. There is also fulcrumed to the rear side of the frame B the stop-pawl E⁴, adapted to be in constant contact with the ratchet-wheel D¹⁰. This pawl E⁴, like the other pawls, is held in position by means of a spring. 90

To the side of the frame B behind the ratchet-wheel D¹⁰ is secured one end of the spring F', the other end of which is provided with the locking-pin F², adapted to engage with the perforations F³ (see Figs. 10 and 11) 105 of the year type-sector L, the web L² of which is split and sprung over the flanged collar L³, secured to the inside of the frame B. 100

Upon the inner side of frame B, and beneath the month-sector K, is secured an arm K', the upper end of which bears a spring-actuated toe or trip K². Upon the adjacent face of the day-wheel is secured a metallic spring-ring K¹⁰, the lower portion of which is provided with a toe or projection K³, slightly 115 curved outwardly, as shown more clearly in Figs. 7 and 9. The spring-ring K¹⁰ is sunk within a recess upon the face of the day-wheel of sufficient depth that normally the toe K³ will not engage the beveled ratchet-teeth k' upon the lower side of the month-sector K. When, however, the day-wheel I has rotated far enough, the projection or toe K³ will come into contact with the inclined face m of trip K² and be moved outward into 120 the space between the teeth of the month-sector K, where, upon further movement, it will cause the said sector to turn a distance equal to the distance between two of its teeth. When the toe K³ has passed the trip K², it 125 will spring back into its position in the recess in the day-wheel. When it is expedient or necessary, the day-wheel or month-sector may be turned backward, the toe K³ passing 130

over the trip K^2 , which is provided with a spring a^2 to return it to and hold it in its normal position. There is also the pawl K^5 , secured to the frame B beneath the month-sector K, said pawl being adapted to engage with the circumferential ratchet of said sector K.

It must be observed that all of the deer-foot pawls, together with the trip or toe herefore mentioned, are provided with the springs a^2 , adapted to hold their parts in their normal position.

Having thus described my invention, what I claim as new, and desire to secure by Letters Patent, is—

15 1. In combination, a frame, a cam mounted to turn therein, an arm pivoted or fulcrumed to said frame and carrying at one end a spring-pawl bearing upon the cam, and an adjustable conical screw in said frame bearing upon the free end of the arm to regulate the force with which the spring-pawl shall bear upon the cam.

20 2. In a time-stamp, the combination of the time mechanism, the indicator mechanism, including the ratchet-wheel M, a deer-foot pawl R, mounted in the frame of the indicator mechanism in position to engage the wheel M, and connected with the time mechanism, to be oscillated thereby, the said pawl having a toe i and curved extension R' , substantially as shown, and for the purpose stated.

25 3. A time-stamp having the shaft E, the indicator-wheel F and ratchet fixed thereon, the wheels I and G, provided with sleeves also provided with ratchets, the said wheels being arranged on the shaft on opposite sides of the wheel F, the sectors H and K, turning on the sleeves of the wheels I and G, and the sector L, means, substantially as described, for 30 operating the sector K from the wheel I, com-

bined with time mechanism, with cams and pawls mounted upon the frames of the indicator and time mechanisms, and suitable connections between them, whereby the indicator wheels and sectors are operated from the time mechanism, as described.

4. The combination, with time mechanism, of time-indicator mechanism comprising a main shaft, time-indicators supported upon said shaft, ratchets and pawls for operating 45 said indicators mounted upon the time-indicator frame, ratchets and pawls mounted upon the frame for the time mechanism, connections between said pawls, arms upon which said pawls are borne, and adjusting 50 devices acting on said arms for varying the resistance of the pawls, substantially as specified.

5. The combination, with time mechanism, of time-indicator mechanism, ratchets and 55 pawls for the indicator mechanism, and suitable connections between the time mechanism and the time-indicator mechanism, whereby the latter may be operated by the former, and a setting device consisting of a shaft 60 having a turning head and a pinion to engage a gear on the hour-shaft, by which both the time mechanism and the time-indicator mechanism may be set in unison, substantially as specified.

6. The combination, in a hand-stamp, of the shaft E, sleeved day or type wheel I, ratchet-wheel M, and a self-adjusting deer-foot pawl provided with an extension adapted to catch the said ratchet-wheel M when another pawl 75 is being released therefrom.
